UNITED STATES PATENT OFFICE.

JOSEPH RABER, OF POPLAR BLUFF, MISSOURI, ASSIGNOR, BY MESNE ASSIGNMENTS, TO THE DALTON ADDING MACHINE COMPANY, OF CINCINNATI, OHIO, A CORPORATION OF OHIO.

TYPE-WRITING MACHINE.

1,129,012.

Specification of Letters Patent. Patented Feb. 16, 1915.

Application filed July 12, 1908. Serial No. 444,244.

To all whom it may concern:

Be it known that I, JOSEPH RABER, a citizen of the United States, residing at Poplar Bluff, Missouri, have invented a new and useful Type-Writing Machine, of which the following is a specification.

This invention relates to typewriting machines, and more particularly to devices for adjusting and feeding the paper; and it consists of the novel construction, combination and arrangement of parts herein shown, described and claimed.

The object of the invention is to provide a device in connection with the platen carriage of a typewriter whereby a sheet of paper which is inserted into the machine longer than once may be adjusted so that the records made at the different insertions will be in exact alinement and at uniform distances apart. In this way a bill, for instance, may be inserted in the machine to receive a record each time any goods are sold, and these different records made at different times will be in the same exact relation to each other that they would be if made at a single passage of the paper through the machine.

In the drawings forming part of this specification, Figure 1 is a front elevation of a platen and platen carriage showing my invention embodied therein. Fig. 2 is a side elevation thereof. Fig. 3 is a front view of a paper table adapted to be used in connection with another form of adjusting device or gage. Fig. 4 is a side view of the table and gage of the modified construction.

In the embodiment of my invention shown in the drawings a gage is provided at the feeding-in side of the platen, above the paper table, to serve as an abutment for the rear edge of the paper, and another gage is provided at the side of the paper table as a guide for the side edge of the paper.

The case of the machine is indicated by 1, the platen carriage by 2, the platen by 3, the carriage rails or truck members by 4, and the carriage rollers by 5. A type-bar is shown at 6 in Fig. 2 in position to strike the front of the platen. The lower feed rollers are shown at 7, and cooperate with the platen to feed the paper through the machine and to move the paper in either direction therein. A paper guide 8 at the feeding-in side of the platen serves to guide the leading edge of the paper between the feed

rollers and the platen when the paper is being started into the machine. Thence the paper passes upwardly against the front surface of the platen which is the printing surface, and feeds backwardly over the paper table and gage so as not to interfere with the operation of the type-bars nor with the operator's view, of the record as it is made.

The paper table 9 is supported at the rear side of the platen carriage. From this table the paper passes downward toward the platen and onto the guide 8, and thence under the platen and upward in front of the platen. At the rear edge of the paper table an upturned flange 10 is formed parallel with the platen axis and a similar flange 11 is provided at one side of said table, said flanges constituting gages for the rear and side edges of the paper. When the paper is introduced into the machine it is fed forwardly until its rear edge passes below the gage flange 10, whereupon the lower feed rollers 7 are released from the paper. The rear edge of the paper is then drawn backward until it abuts against the gage 10, and the paper is moved laterally until its side edge is against the side gage 11. The rollers 7 are then permitted again to bind the paper and the platen may be manually rotated to feed the paper in either direction as required to adjust the paper for record. The usual platen-knobs 12 attached to the ends of the platen shaft afford means for manual rotation of the platen.

It will be noted that the gage 11 is separated from the gage 10 by an intervening space 11^a which constitutes a passage affording access to the edges of the sheets of paper. The provision of the space 11^a enables the operator to engage the edges of the paper manually or to insert an implement between the sheets of paper and the paper table 9 to raise the sheets of paper above or in front of the gages. By thus enabling the operator to engage both edges of the paper it is apparent that the superposed sheets of paper may be more accurately and readily adjusted.

The modification, or alternative construction, shown in Figs. 3 and 4, comprises a paper table 13 which is intended to occupy the position and take the place of the table 9. At the side edges of the table 13 are

- rearwardly extending ears 14 by which a gage plate 15 is pivotally united with the table 13. A series of perforations or slots 16 are formed adjacent to the rear and one of the side edges of the table 13 and a like series of gaging points or flanges 17 are formed along the edges of the gage plate 15. A spring 18 between the gage plate and the table 13 holds them apart so that the paper 5 may be inserted without obstruction for ordinary writing. One of the gaging points 17 is bent to form a hook 19 which engages with a hook 20 on the table 13 and limits separation of the two parts. The hook 20 10 may be formed by bending the material from a slot 21, which is in the row or series of slots 16. The point 17 which supports the hook 19 is also in the line or row of gaging points so that when it projects through the slot 21 all of the gaging points at the rear 15 will be in a straight line. But when accurate adjustment of the paper is desired, as for billing, the paper is brought below and to one side of the perforations 16 and the gaging points or flanges 17 caused to protrude through the perforations 16 to act as gages for the side and rear edges of the paper. Then the paper is moved laterally and backwardly to abut against these protruding points or flanges, and in this way is 20 accurately adjusted. When the paper has been adjusted the spring 18 forces the table 13 back to its normal position, presenting a plane surface.
- 25 It will be noted by reference to Fig. 4 that the uppermost gage point 17 at the side is separated from the adjacent rear gage point 17 by a space 17^a which affords access to the paper similar to the space 11^a, previously described. Thus, the paper may readily be engaged at the side edge which is adjacent to the side gages in either embodiment of the invention, so that the different sheets of paper may be more accurately adjusted with 30 respect to each other.
- 35 By use of this device a sheet of paper may be repeatedly inserted in the machine, and removed, and the record made at each insertion can be made to fall exactly in proper position with respect to the preceding record, so that the result of the various records is a neat and accurate copy. It avoids the necessity of laborious and tedious adjustment of the paper with respect to the platen-scale and enables the operator to make rapid and accurate adjustment of the paper without special attention or care beyond causing the edges of the paper to abut against the edge gages.
- 40 I am aware that there may be variations from the specific construction described without in the least departing from the spirit and scope of my invention.
- 45 I do not restrict myself to exact features of construction, but

What I claim and desire to secure by Letters Patent is:

1. In a typewriting machine, the combination with a platen, a guide plate for guiding paper to the platen, and a paper table extending obliquely upwardly and rearwardly from said guide plate at the feeding-in side of the platen, of a flange at the rear edge of said paper table parallel with the platen axis, and a flange at the side edge of said paper table, said two flanges being rigid with respect to each other and separated by an intervening space affording access to the edges of the paper adjacent to said side flange, substantially as specified. 70
2. In a typewriting machine, the combination with a platen, means for rotating said platen effectively to feed paper forwardly and rearwardly, a guide plate for guiding the paper to the platen, and a separate paper table extending obliquely upwardly and rearwardly from said guide plate at the feeding-in side of the platen, of a flange at the rear edge of said paper table parallel with the platen axis, and a flange at the side edge of said paper table above said guide plate in a plane at right-angles to the plane of the first-named flange, said flanges being rigid with respect to each other, substantially as specified. 75
3. The combination with a platen, of a plate for guiding the paper to the platen, a gage plate, a paper table having a series of aligned slots near its rear edge, a hinged connection uniting said gage plate and said paper table, gaging points on said gage plate adapted to be extended through said slots, a spring effective to hold said gaging points out of said slots, and engaging hooks limiting movement of said gage plate from said paper table, substantially as specified. 80
4. The combination with a platen, of a paper table for guiding the paper toward the platen, gage elements at the rear portion and at the side edge of said paper table and being movable into and out of operative position, and means actuating said gage elements out of operative position, substantially as specified. 85
5. The combination with a platen, means for rotating said platen to feed paper forwardly and rearwardly, and type for recording on paper held by the platen, of a paper table for guiding the paper toward the platen, a gage at the rear portion of said paper table for the rear edge of the paper, said gage being movable into and out of operative position, and means actuating said gage out of operative position, substantially as specified. 90
6. The combination with a platen, and type for recording on paper held by said platen, of a paper table for guiding the paper toward the platen, a gage at the rear portion of said paper table for the rear edge. 95

of the paper and at the side portion of said paper table for the side edge of the paper, means for actuating said gage away from said paper table, and engaging hooks on 5 said gage and on said paper table limiting movement of said gage away from said paper table, substantially as specified.

7. The combination with a carriage, a platen mounted in said carriage, and a guide 10 plate extending obliquely upwardly and rearwardly from the under side of said platen, of a paper table supported in said carriage for guiding the paper toward said guide plate, a gage at the rear portion of 15 said paper table for the rear edge of the paper, a gage at the side edge of said paper

table for the side edge of the paper, said gages being rigid with respect to each other, means actuating said gages away from said paper table, and engaging hooks on said paper table and on one of said gages limiting movement of said gages away from said paper table, substantially as described. 20

In testimony whereof, I hereunto affix my signature to this specification this 12th day 25 of June, 1908, in the presence of two witnesses.

JOSEPH RABER.
